ABSTRACT: A double-tuned circuit in which a capacitor is connected to offset the effect of internal tube or transistor reactances and permit up to unity mutual coupling in an interstage circuit. In a preferred embodiment, a metallic cylinder positioned around the tube is used as the external cathode lead to lower its inductance.

DOUBLE-TUNED CIRCUIT

BACKGROUND OF THE INVENTION

The well-known double-tuned circuit is often used to couple the stages of a multistage amplifier. Of particular significance in such double-tuned circuits are critical coupling and transitional coupling. Critical coupling may be defined as the degree of mutual coupling between the primary and secondary circuits at which maximum power transfer is achieved, that is, where the primary circuit resistance is transformed to equal the secondary circuit resistance. If the coefficient of coupling is increased beyond critical, transitional coupling may be achieved. At transitional coupling, the maximum flatness of the passband of the double-tuned circuit is achieved. For any coupling greater than transitional, a double humped response will occur, while for any coupling less than transitional, a single response of narrower band width is obtained. However, maximum power transfer is not obtained at transitional coupling except in a special case of equal primary and secondary Q when transitional coupling and critical coupling are equal.

In the design of wide band amplifiers, it is frequently desirable to obtain the maximum possible bandwidth in each interstage circuit as limited by parameters of the active amplifier elements which have inherent input and output resistances and series and shunt reactances. For example, in a wideband vacuum tube amplifier operated in the VHF or UHF frequency regions the lead inductances, shunt impedances and input and output resistances are critical to the achievement of maximum bandwidth and power transfer. The significant parameters of the tubes themselves are the cathode and plate series inductances and the cathode grid and grid-plate capacitances. At frequencies above several hundred megahertz, the lead inductance internal to the tube envelope is appreciable in even the best tubes designed for this purpose. In addition, the capacitive reactance from cathode to grid and from plate to grid become very low compared to the input and output resistances of the tube at these higher frequencies thereby increasing the Q of the input and output circuits and making the achievement of broad bandwidths difficult or impossible unless external loading decreases the power gain of the stage more than the bandwidth is increased, resulting in a decreased power gain bandwidth product. Consequently, external loading is an undesirable and frequently unacceptable means of obtaining broad bandwidth in an RF power amplifier.

In the double-tuned circuit it is necessary that the primary and second circuits each individually be turned to a frequency at or near the center of the desired band-pass of the circuit. This requires a specific relationship between the total capacitance and inductance of both the primary and secondary circuits, as the total inductance which can be used in either primary or secondary circuit to resonate that half of the circuit is determined by the total shunt capacity. As a consequence of this fact and because of the inductance present in the cathode and plate leads of the tube internal to the tube envelope, the total amount of mutual inductance which can be employed is limited in the conventional double-tuned circuit since the mutual inductance is of necessity external to the tube itself. However, because of the magnitudes of the internal reactances of the tubes, and the normal loads to be encountered, the Q's of the primary and secondary circuits may be such to require a coefficient of coupling which can be achieved only by using a mutual inductance larger than that which permits secondary circuit resonance to be achieved. As a consequence transitional coupling cannot be achieved.

This problem is aggravated because of the relatively high inductance of those connectors, such as straps or bars, which are conventionally used as the external cathode lead. Large reactances in the coupling circuit reduce the network bandwidth and thus decrease the performance of the circuit.

SUMMARY OF THE INVENTION

According to the present invention, sufficient coupling to achieve transitional or even overcoupling can be obtained by the addition of an external series capacitive reactance in the secondary circuit to cancel the inductive reactance of the internal cathode lead at the center frequency of the amplifier. This effective reduction in secondary circuit inductive reactance permits the use of a large enough mutual inductance to permit transitional coupling. In order to make the bandwidth as broad as possible, it is desirable to reduce the external cathode lead to as small an inductance as possible, thus also permitting the use of a smaller compensating capacitor. This is accomplished according to the present invention by providing this cathode lead inductance in the form of a cylinder which surrounds the tube and which serves as the internal conductor of a coaxial cable, the outer conductor of which is the housing in which the circuitry is located. The inductance of the cylinder is thus a function of the diameter of the cylinder and its spacing from the outer wall.

Although the external capacitor inserted in the secondary produces zero net reactance only at the center frequency, at a frequency ± 10 percent from band center, the net inductive or capacitive reactance of the capacitance and inductance in series is only 20 percent of the original reactance of the cathode inductance. This is still small enough to permit transitional or greater than transitional coupling to be achieved in the interstage circuit. This permits bandwidths of 20 percent—30 percent of center frequency to be achieved with transitional coupling by the simple expedient of resonating the cathode lead inductance internal to the tube by an external series capacitance.

BRIEF DESCRIPTION OF THE DRAWINGS

FIG. 1 is a schematic diagram of a conventional double-tuned circuit interconnecting two amplifier tubes;

FIG. 2 is a schematic diagram of the circuit of the present invention;

FIG. 3 is a top plan view of a structural embodiment of the circuit of the present invention;

FIG. 4 is a sectional view taken along lines 4-4 of FIG. 3;

FIG. 5 is a perspective view of a portion of the structure of the present invention and;

FIG. 6 is a sectional view taken along lines 6-6 of FIG. 5.

DESCRIPTION OF THE INVENTION

The problems overcome by the present invention and the improved operation resulting therefrom may be better understood by discussion of a typical example of a prior art circuit such as that shown in FIG. 1. This circuit will be recognized as a double-tuned circuit connecting two stages of an amplifier with k the internal reactances of the tubes and the external reactances being illustrated. As shown, tubes 10 and 11 are connected as grounded grid amplifiers and are suitable for use in the UHF and higher frequency regions. These tubes, for example, may be Type 7911 manufactured by the General Electric Company. The grid to plate capacitance C_P of the tube 10 is illustrated by the capacitor 12 while the internal plate lead inductance L_P of the tube 10 is illustrated by the inductance 13. In a similar manner, the cathode to grid capacitance C_k of the tube 11 is illustrated by the capacitor 14 while the internal cathode lead inductance L_k is illustrated by the inductor 15. As shown, the tube circuits are interconnected by the T equivalent of a double-tuned circuit comprising series inductors 16 and 17, and the shunted mutual inductance (L_M) 18. A blocking capacitor 19 is provided to prevent the DC on the plate of the tube 10 from being grounded through the inductor 18.

Let us now analyze the circuit shown in FIG. 1, keeping in mind the desirability of operating the circuit at transitional coupling. Assuming that the amplifier is operating at 1000 75 MegaHertz with the grounded grid triodes 10 and 11 having a

shunt input capacitive reactance of $-j$ 25 ohms and a cathode lead inductive reactance internal to the tube of $+j$ 8 ohms. Assume the external cathode lead reactance to be $+j$ 10 ohms. Since the total inductive reactance must equal the total capacitive reactance at the center frequency, the maximum mutual inductance (L_M) is $+j$ 7 ohms. A representative load resistance presented by the grid-cathode tube input at these frequencies would be approximately 30 ohms resulting in a secondary circuit Q of 1.2 ($R_K/C_K=30/25=1.2$).

Representative values of the output impedance of the tube would be $r_p=2,000$ ohms, the plate to grid capacitance 11 of the tube $-j$ 60 ohms, and the internal plate lead inductance 13 of the tube $+j$ 30 ohms. The blocking capacitor 19 would have a reactance of $-j$ 15 ohms and the external inductance 16 a reactance of $+j$ 33 ohms. As a consequence, the Q of the primary circuit, that is, $r_p/X_{cp}=2,000/60=33.33$. By reference to the literature, for example, *Electronic Designers's Handbook* by Landee, Davis and Albrecht, FIG. 13.21, it can be found that to achieve transitional coupling with a secondary Q of 1.2 and a ratio of Q primary to Q secondary of 27.78, the required coefficient of coupling is approximately 0.45. Since the total primary circuit inductive reactance must equal $+j$ 75 ohms and the total secondary inductive reactance must equal $+j$ 25 ohms, the required mutual inductance to achieve transitional coupling is found from the equation:

$$M=k\sqrt{L_p L_s}$$

Where:

M =mutual inductance between primary and secondary,
 k =coefficient of coupling.
 L_p =primary circuit inductance.
 L_s =secondary circuit inductance.

The required mutual inductance is thus found to be 19.5 ohms. However, because the internal cathode lead inductance 15 of the tube 11 is $+j$ 8 ohms and the external cathode lead inductance 17 is $+j$ 10 ohms, secondary circuit resonance cannot be achieved with a mutual inductance which is larger than $+j$ 7 ohms. As a consequence, transitional coupling cannot be achieved.

FIG. 2 shows the circuit of FIG. 1 modified in accordance with the present invention. The circuit shown in FIG. 2 is almost identical with that shown in FIG. 1, and similar reference numerals are used to designate similar elements. As can be seen, a capacitor 20 has been added in the external portion of the secondary circuit of FIG. 2. The value of this capacitor is chosen so that the secondary circuit can be made to resonate even though the value of the mutual inductance 18 is selected in accordance with criterion other than simply those of the secondary circuit. Thus, in the example given previously, the capacitor 20 would have a capacitive reactance of $-j$ 12.5 ohms. This permits the mutual inductance 18 to be increased by 12.5 ohms, that is, up to the 19.5 ohm level that is required. Consequently, transitional coupling is achieved and the greatest possible power gain-bandwidth product is obtained.

Turning now to FIGS. 3, 4, 5 and 6, there is shown a structural embodiment of the circuit shown in FIG. 2. A conductive housing 24 of aluminum or the like which serves as circuit ground is mounted on an assembly 25 which may contain other portions of the electrical system with which the amplifier is used. The housing 24 is provided with a groove 26 on its upper surface which receives an O-ring 27 which cooperates with a cover plate 28 to seal a chamber 29 within the housing 24 from moisture or other contaminants.

The housing 24 is provided with a series of lips 30 that protrude into the chamber 29. Each pair of lips 30 cooperate with a clamp 31 to support a vacuum tube 32 and to make contact to the grid thereof. As can best be seen in FIG. 6, the clamp 31 consists of a pair of plates 33 and 34 whose ends are slightly hooked so as to form clamps for grasping the lips 30. The plates 33 and 34 are positioned on either side of the grid contact area 35 of the tube 32 and then spot-welded or otherwise fastened together so as to hold the tube firmly in place. The tube 32, as previously mentioned, is preferably a General Electric Type 7911. Contact to the cathode contact area 36 of

the tube is made by a cylinder 37 that is positioned over the cathode end of the tube. The bottom plate 38 of the cylinder 37 serves as one plate of a capacitor, the other plate of which is a bracket 39 connected to one side of the housing 24 and the dielectric of which is one or more sheets 40 of a suitable material such as polytetrafluoroethylene sold by DuPont under the trade name Teflon.

5 A capacitor 41 is connected to the bracket 39 between its ends and is, in turn, connected through a sliding bar type variable inductance 42 to the anode pin 43 of the next tube. This sequence of connections is repeated as many times as desired. If desired, the cylinder 37 can be provided with a slot 43 to permit access to the tube of the various chokes which are conventionally used with such tubes. If desired, a slot can be provided on both sides of the cylinder but it is preferable that the slots not extend the whole length of the cylinder so that a connection remains between the upper and lower halves thereof. If desired, the cylinder 37 can be made shorter and the capacitor formed on a surface thereof by positioning the dielectric and the other plate in a saddlelike manner on the surface.

10 Each of the electrical elements shown in FIG. 2 finds its structural manifestation in FIG. 3. The tubes 10 and 11 correspond to the successive tubes 32 in FIG. 3. The capacitor 12 and inductor 13 and capacitor 14 and inductor 15 are internal impedances of these tubes as pointed out previously. The inductor 16 of FIG. 2 corresponds to the variable inductor 42 of FIG. 3. The capacitor 19 of FIG. 2 corresponds to the capacitor 41 of FIG. 3. The mutual inductance 18 of FIG. 2 corresponds to that portion of the bracket 39 from the capacitor 41 to the housing 24, that is, to ground. The capacitor 20 is made up of the bracket 39, dielectric 40 and plate 38 of FIG. 3. The inductor 17 of FIG. 2 corresponds to the cylinder 37 of FIG. 3.

15 25 30 35 The use of the cylinder 37 as the external cathode lead inductance of the tube permits this inductance to be substantially reduced over other inductances commonly used for this purpose. The cylinder acts as the inner conductor of a coaxial cable, the housing 24 acting as the outer conductor thereof.

40 45 40 The inductance the cylinder presents is a function of its diameter and its spacing from the outer wall of the housing 24, or in this case, the base of the housing 24 and the cover plate 28 since they are the closest surfaces of the housing. The actual impedance of the cylinder and its inductive reactance can be determined by conventional mathematics and need not be discussed here.

45 50 55 From the foregoing description, it can be seen that a double-tuned circuit has been provided which permits the desired condition of transitional coupling to be achieved even when the circuit is operating at frequencies high enough to require that the internal reactances of vacuum tubes be taken into account as circuit components. A unique structural configuration has also been provided which permits the external cathode lead inductance of the tubes utilized to be reduced therefore permitting the value of the compensating capacitor to be reduced and the bandwidth of the system increased.

50 60 65 The invention may be embodied in other specific forms not departing from the spirit or central characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

I claim:

70 75 1. In a circuit for coupling a pair of amplifying means at frequencies at which the internal reactances of the amplifying means becomes significant circuit parameters and including a double-tuned circuit having a primary circuit, a secondary circuit and a mutual inductive reactance common to said primary and secondary circuits; said primary circuit including as reactive components the internal inductive and capacitive reactances of the first of said amplifying means and the inductive reactance of an output connector coupled to said first am-

plifying means; said secondary circuit including as reactive components the internal inductive and capacitive reactance of the second of said amplifying means and the inductive reactance of an input connector coupled to said second amplifying means; the improvement comprising an external capacitive reactance connected in said secondary circuit, the value of said external capacitive reactance being selected to offset a portion of the inductive reactance of said secondary circuit to permit said mutual inductive reactance to be chosen to obtain transitional coupling between said primary and secondary circuits while maintaining secondary circuit resonance.

2. In a circuit for coupling a pair of amplifying means each having an input electrode, an output electrode and a control electrode at a frequency at which the internal reactances of the amplifying means become significant circuit parameters and including a double-tuned circuit having a primary circuit, a secondary circuit and a mutual inductive reactance common to said primary and secondary circuits; said primary circuit including as reactive components the control electrode-output electrode capacitive reactance and the output electrode inductive reactance of the first of said amplifying means and the inductive reactance of an output connector coupled to the output electrode of said first amplifying means; said secondary circuit including as reactive components the input electrode-control electrode capacitive reactance and the input electrode inductive reactance of the second of said amplifying means and the inductive reactance of an input connector coupled to the input electrode of said second amplifying means; the improvement comprising an external capacitive reactance coupled in said secondary circuit in series with said input connector inductive reactance, the value of said external capacitive reactance being selected to offset a portion of the inductive reactance of said secondary circuit to permit said mutual inductive reactance to be chosen to obtain transitional coupling of said frequency between said primary and secondary circuits while maintaining secondary circuit resonance.

3. The circuit of claim 2 wherein said control electrodes of said amplifying means are grounded.

4. The circuit of claim 2 wherein said amplifying means comprise space discharge devices each having a cathode, an anode and a grid.

5. The circuit of claim 2 wherein said primary circuit includes a blocking capacitor.

6. The circuit of claim 2 wherein said input connector comprises one conductor of a coaxial cable.

7. The circuit of claim 6 wherein said input connector comprises a cylinder positioned around said second amplifying means.

8. The circuit of claim 7 wherein the other conductor of said coaxial cable comprises a housing in which said amplifying means are mounted.

9. The circuit of claim 8 wherein said external capacitive reactance comprises a portion of said cylinder, dielectric means positioned thereagainst, and bracket means positioned 10 against said dielectric means and connected to said housing.

10. The circuit of claim 9 wherein said portion of said cylinder comprises a base plate fastened thereto.

11. An amplifying circuit for use at frequencies at which the internal reactances of amplifying means become significant

15 circuit parameters comprising: first and second amplifying means each having an input electrode, an output electrode and a control electrode; a closed conductive housing for enclosing said amplifying means; clamp means for supporting said amplifying means in said housing and electrically connecting the control electrodes of said amplifying means to said housing; inductive reactance means coupled to said output electrode of said first amplifying means; a conductive cylinder positioned around a portion of said second amplifying means and electrically connected to the input electrode thereof;

20 bracket means mechanically and electrically connected to said housing and extending into proximity with a portion of said cylinder; dielectric means separating said bracket means and said cylinder portion whereby a capacitive reactance is formed; and capacitive reactance means electrically coupling

25 said bracket means at a point intermediate the ends thereof with said inductive reactance means; said named reactances and said internal reactances of said amplifying means forming a double-tuned circuit with the portion of said bracket means from said point intermediate the ends thereof to said housing

30 being the mutual inductance of said double-tuned circuit, said capacitive reactance formed by said bracket means, said cylinder and said dielectric means permitting transitional coupling in said double-tuned circuit at said frequencies.

35 12. The circuit of claim 11 wherein said amplifying means comprise space discharge devices each having a cathode, an anode and a grid.

13. The circuit of claim 11 wherein said inductive reactance means comprises a sliding bar variable inductance.

14. The circuit of claim 11 wherein said portion of said cylinder comprises a base plate fastened thereto.
